UNITED STATES PATENT OFFICE.

WILLIAM L. McCABE AND CHARLES H. ANDERSON, OF TACOMA,
WASHINGTON.

FREIGHT-TRANSFERRING APPARATUS.

SPECIFICATION forming part of Letters Patent No. 585,221, dated June 29, 1897.

Application filed March 31, 1896. Serial No. 585,278. (No model.)

To all whom it may concern:

Be it known that we, WILLIAM L. McCABE and CHARLES H. ANDERSON, citizens of the United States, residing at Tacoma, county of 5 Pierce, and State of Washington, have invented a new and useful Freight-Transferring Apparatus, of which the following is a full, concise, and exact description, reference being had to the accompanying drawings, forming 10 a part of this specification.

Our invention relates to the transferring of grain and other freight shipped in sacks, boxes, or bales by means of carrying-belts made of rope and so arranged that freight 15 may be transferred from the cars into a freight-house or into a ship, and vice versa, without the use of hand-trucks, commonly used for such work. We do this by means of portable rope-belt conveyers to convey the 20 freight from the cars or ship into the freight-house, where, by means of reversible dumping-tables, it is transferred to a fixed transferring-belt, which conveys it to one or the other end of the building. This belt is provided 25 with portable interlacing elevator-belts, which lift the freight onto another reversible dumping-table, from which it is received by another portable carrier and delivered to any 30 part of the freight-house for storage or to the cars or ship for shipment.

Our invention will be more readily understood by reference to the accompanying drawings, in which—

Figure 1 is a cross-section of a freight-house with a car on one side and a ship on the other. Fig. 2 is a longitudinal section of the freight-house; and Fig. 3 is a plan of the same, showing the arrangement of the apparatus for handling freight. Fig. 4 is a detail perspective of the elevating-conveyer and the dumping-table. Fig. 5 is an enlarged detail of the interlacing ropes of the conveyers. Fig. 6 is a detail perspective of the driving means for main conveyer. Fig. 7 is a side elevation of the same. Fig. 8 is a plan view of Fig. 7. Fig. 9 is a side view of the frame for the conveyer. Fig. 10 is a vertical section and front view of one of the idler-rolls carried by the frame. Fig. 11 is a side view of 45 the tension device for the main conveyer, and Fig. 12 is an end view of the same.

Similar letters refer to similar parts in the several views.

The apparatus consists of a main carrying rope belt constructed on the floor or floors of a 55 freight or ware house, of any length, as shown at A A A, Figs. 1, 2, and 3, where in this instance it is arranged for two floors. By means of the grooved drums B B at one end and drum D at the other, the latter being used as 60 the driving-drum, the belt is run continuously to the right or left, as desired, the loosely-running idlers I I I carrying it on a line parallel with the floors. This belt is constructed of one continuous line of rope, and by means 65 of the tension-wheel H and weight W, suspended from the pulley J, is kept tight at all times. (See Figs. 11 and 12.)

The main belt A is provided with one or more reversible dumping-tables, as indicated 70 at F, F', and F''. These tables are centrally pivoted on a stout frame f f f, as shown in Fig. 4. The upright standards or legs are equally distant from each other, and thus occupy the angles of a square. Under each leg 75 is a pivoted roller t'. On each side of the belt A is a track-rail T T, and the rollers t' run on this track, supporting the table-frame across the belt A and the table F directly over it. The table F is made of sheet metal or 80 other material with sides turned up and pivoted to the frame at the sides, as shown at f'. Suspended on a pivot in this way it can be set to an incline, so as to cause the packages thrown on it to slide to one or the other side, 85 as desired. As shown in Fig. 4, the table T is set to receive freight from the elevator E and will turn it to one side of the belt A onto one of the conveyers C. In order to receive freight from one of the conveyers C, the table-frame 90 is to be lifted clear of the belt A and turned one-fourth round, so F will deliver the freight onto A, the pivoted rollers t' being turned so as to fit track T. Thus the tables F, F', and F'' are reversible and may be rolled along the 95 track T, so as to occupy any position desired over the main belt A.

The elevators shown at E, E', and E'' are constructed as shown in Fig. 4, where they are in position to elevate the freight from the main 100 belt A onto one of the reversible dumping-tables F. It consists of a lower drum d and

an upper drum e , mounted on the side frames EE . Each drum is grooved and provided with a number of single-rope belts adapted to the ropes of the main belt A in number and spacings. The shaft of d is centrally pivoted at g on stout bars $b b$, mounted on rollers $t t$, made to run on the track T . The bars $b b$ are held together by means of the raised cross-bars b' and b^2 . These cross-bars serve as a support to the sides of E , as shown in Fig. 4, and are high enough above A to allow freight to pass under them. The elevator E is reversible and may be turned over to incline to the left and rest on the cross-bar b' . It is to be observed that the drum d is below the main belt A and on a level with the idler I . The elevator rope belts $a a$ pass between the ropes of belt A , and thus make a continuous belt to carry the freight up onto the dumping-table F . Elevator E is provided with a friction-roller d' , which, by means of the adjusting-screws $h h$, is made to roll hard on the ropes of belt A and cause them to ride hard on d , as more clearly shown in Fig. 5. By this means d is made to turn by belt A , and thus the belts $a a$ of E are put in motion to correspond with A . It is to be observed that E can be run along on T to occupy any place desired on the belt A . In order to pass an idler I , one end of the carriage may be lifted by using b' or b^2 as a handle and raising d so as to pass over I , the belt A being raised with d . The conveyers C , C' , or C^2 used to carry the freight to or from the main belt A are constructed as shown by Figs. 6, 7, 8, 9, and 10. The frame is made of four stout pipes or bars $c c c c$ of any desired length, with a drum d^2 , Fig. 6, at one end and drum d^3 , Fig. 9, at the other end. These drums are grooved, as shown in Fig. 8, in which is fitted a rope belt $a' a'$, made of one continuous rope, the same as in main belt A . The pipes $c c$ are framed together by cross pipes or bars $c' c'$ and $c^2 c^2$, making a stout frame. On cross-pipes $c' c'$ are small grooved idlers i , made to carry $a' a'$ along the conveyer-frame. The belt is operated by means of the wheels K and L . Supposing the belt being run so as to carry goods from d^2 to d^3 , wheel L takes the rope from the left end of d^2 and carries it down one-half round and transfers it to wheel K , which transfers it to the right end of d^3 , as indicated in Figs. 7, 8, and 9. By this means the rope is transferred from one side to the other of the belt, as required in a belt made of one continuous rope. The wheel L has a shaft with sliding bearings adjusted by hand-screws, as shown at h' , by means of which the belt may be kept tight. The belt is driven by an electric motor M , which turns the worm-wheel N with gear-wheel attached to the shaft of K , all of which is indicated in Figs. 6, 7, and 8. It is to be observed that the conveyers C , C' , and C^2 are made to weigh as little as possible, so as to be portable. They are to be carried from place to place about the building.

In conveying freight to the upper floor the elevator E takes it from the main belt on the first floor and dumps it onto the angled board or chute-slide G , on which it passes around and onto the belt leading to the upper floor. By means of the elevator E^2 it is thrown on the dumping-table F^2 , which delivers it to conveyer C^2 , from which it is stored. (See Figs. 1, 2, and 3.)

Having described our apparatus in detail, its operation is practically as follows: Supposing freight is to be taken from the car R to the ship S , the sacks or bales are thrown on the conveyer C and by it conveyed to the dumping-table F , which turns it onto the main belt A , on which it is carried to the elevator E' , where it is raised to the table F' , on which it is turned upon the conveyer C' and delivered by it to the ship S . Should we be taking freight from the ship to the car, elevator E' would be moved to F and reversed so as to lift goods passing from right to left, the carrying-belts would be reversed in motion and the dumping-tables reversed to work with them, and the work would proceed as before, only in the opposite direction. It is to be observed that should conveyer C be set opposite C' the work can be done without the use of the main belt A .

To carry the freight into the warehouse, it is delivered to the main belt over conveyers C or C' , and from that by means of elevator E' or E^2 and tables F' or F^2 it is thrown upon a short conveyer, as C^2 , and delivered to any part of the building. It is to be observed that the conveyer C^2 can be raised or lowered so as to deliver the freight on a level with the top of the pile, and thus save the labor of lifting it into place, and also in taking freight from the warehouse the conveyer can be lowered so the sacks or bales may be rolled down upon the belt without lifting, and, further, the elevators, dumping-tables, and conveyers being movable they can be moved to or from the goods as they are being removed or stored.

It is evident that our invention is susceptible to modifications to meet peculiar requirements, and we do not therefore desire to limit ourselves to minute details of construction as to dimensions, number of parts, and the kind of materials required in the apparatus.

We are aware that previous to our invention various forms of carrying-belts and elevators have been in use by others. We therefore do not claim such as our invention singly or broadly, but,

Having described our invention, what we claim as new, and desire to secure by Letters Patent, is—

1. In a transferring mechanism, the combination with a main conveyer, of an elevating-conveyer extending longitudinally above the main conveyer and adapted to be moved longitudinally of said main conveyer and to receive material therefrom, substantially as described.

2. In a transferring mechanism, the combination with the main conveyer, of an elevating-conveyer extending longitudinally of the main conveyer and mounted so as to be reversed in its longitudinal relation to said main conveyer and to receive material therefrom whereby the same may be conveyed toward either end of the main conveyer, substantially as described. 5
3. In a transferring mechanism, the combination with a main conveyer, of a longitudinally-movable support, and an elevating-conveyer extending longitudinally of the main conveyer and pivoted to said support so as 10 to be capable of inclination in the direction of either end of the support, substantially as described. 15
4. In a transferring mechanism, the combination with a main conveyer composed of a series of belts, of a movable support, an elevating-conveyer extending longitudinally of the main conveyer and composed of a series of belts lying between the belts of the main conveyer and carried by said support so as 20 to be longitudinally movable along the length of the main conveyer, substantially as described. 25
5. In a transferring mechanism, the combination with a main conveyer composed of a traveling belt, an elevating-conveyer adapted to receive material therefrom, a driving-roll beneath said main conveyer and adapted to drive said elevating-conveyer, and a pressure-roll located above said main conveyer and 30 adapted to hold the same in frictional contact with the driving-roll of the elevating-conveyer, substantially as described. 35
6. In a transferring mechanism, the combination with a main conveyer, of an elevating-conveyer extending longitudinally upward above said main conveyer adapted to receive material therefrom, and a dumping-table located above said main conveyer and adapted to receive material from the elevating-conveyer and to discharge the same at an angle to said conveyer, substantially as described. 40
7. In a transferring mechanism, the combination with two conveyers extending at an angle to each other, of a support movable longitudinally of one of said conveyers, and a dumping-table pivoted to said support and adapted to receive material from one conveyer and discharge the same in opposite directions upon the other conveyer, substantially as described. 45
8. In a transferring mechanism, the combination with a conveyer, of a longitudinally-movable support, a transverse inclined dumping-table centrally pivoted upon said support and adapted to be tilted in opposite directions to discharge material received from said conveyer upon either side thereof, substantially as described. 50
9. In a transferring mechanism, the combination with a main conveyer, of an auxiliary conveyer located at an angle thereto, a reversible frame longitudinally movable over 60 the main conveyer, and a pivoted dumping-table carried by said frame, whereby the frame and table may be adjusted to receive material from either conveyer and deliver the same to the other conveyer, substantially as described. 65
10. In a transferring mechanism, a portable conveyer composed of a belt, a supporting-frame having bearing-rolls at opposite ends, idler-rolls extending transversely of said frame to support said belt, a driving-motor located upon a transverse support carried by said framework and lying between the upper and lower layers of said belt, a driving-wheel located upon a support carried by said frame and over which said belt passes, and means connecting the driving wheel and motor, substantially as described. 70
11. In a transferring mechanism, the combination with a main conveyer, of an auxiliary conveyer located at an angle thereto, and a vertically-inclined pivoted dumping-table supported upon a reversible frame and situated at the junction of said conveyers and adapted to discharge material received from one of said conveyers in opposite directions upon the other conveyer, substantially as described. 75
12. In a transferring mechanism, the combination with a main conveyer, of an auxiliary conveyer extending at an angle thereto, an elevating-conveyer extending longitudinally upward from the main conveyer, and a vertically-inclined pivoted dumping-table located above the main conveyer to receive material from said elevating-conveyer and discharge the same in opposite directions, substantially as described. 80
13. In a transferring mechanism, the combination with a traveling conveyer, a vertically-inclined elevating-conveyer extending longitudinally above the same and adapted to receive material from the upper surface of said traveling conveyer, a second traveling conveyer located in a plane above said first traveling conveyer, and a vertically-inclined chute to receive material from said elevating-conveyer and discharge the same upon the upper surface of the second traveling conveyer, substantially as described. 85
14. In a transferring mechanism, the combination with a main conveyer, of a supporting-carriage adapted to be moved longitudinally thereof, an elevating-conveyer extending longitudinally above said main conveyer and centrally pivoted upon said carriage so as to be reversed to face either end thereof, and transverse supports located at opposite ends of said carriage and adapted to support the elevating-conveyer when in its inclined position, substantially as described. 90
15. In a transferring mechanism, the combination with a conveyer having sheaves at opposite ends, of an endless belt passing over said sheaves in a series of parallel lines, a vertical bearing-wheel, and a horizontally-disposed transferring-wheel around which 95

said belt is carried so as to transfer the belt from the upper portion of one end of one sheave to the lower portion of the opposite end of the other sheave, substantially as described.

16. In a freight-transferring mechanism, the combination with a traveling conveyer composed of rope belts extending on two or more floors of a warehouse, an elevating-conveyer extending above the same and composed of rope belts interlacing with the belts of the traveling conveyer, and an angled chute lo-

cated to receive material from the elevating-conveyer and deposit it upon the upper portion of the traveling conveyer, substantially as described.

In witness whereof we hereunto subscribe our names this 23d day of March, A. D. 1896.
